ROTARY DEVICE FOR PRINTING, SLITTING AND REWINDING ELONGATED WEBS

Julius Schmutz, Glenview, Ky., assignor to Schmutz Manufacturing Company, Incorporated, Louisville, Ky., a corporation of Kentucky

Filed June 13, 1955, Ser. No. 514,940

16 Claims. (Cl. 101—178)

In rotary presses for printing elongated webs of paper, it is necessary to feed the paper to the press under tension and maintain it within the press under tension. While the degree of tension unquestionably varies from time to time and from place to place within the press, it normally does not vary to such an extent as to affect register seriously or prevent the securing of consistently good printing results. These paper printing presses, however, do not give consistently good printing results in the printing of deformable webs composed of polyethylene and other like readily deformable materials. When these materials are subjected to tension and to varying degrees of tension, they become permanently elongated, wrinkled or otherwise deformed and such deformation prevents the securing of good register and of consistently good printing results.

The principal objects of this invention are: to provide a novel rotary press which is capable of giving consistently good results in printing elongated deformable webs composed of materials such as polyethylene; to provide an extremely simple form of rotary device for such printing; and to provide one which may be easily, quickly, simply and inexpensively converted from a rotary polyethylene press to a rotary paper press and vice versa.

In printing elongated webs of sheet material for the bag manufacturing art, it is customary to follow the printing operation with a rewinding operation in which the web is rewound back into a roll which can then be processed into bags by the bag manufacturer. Rewinding into a satisfactory roll, however, presents its difficulties with the result that, in most of the printing presses having a rewinder, the greater part of the entire unit is taken up by the rewinding mechanism. In fact, it is not uncommon to find the rewinding mechanism costing more than the rotary printing mechanism.

Other important objects of this invention are: to provide a rewinding mechanism which is of extremely simple nature; to provide one which will consistently rewind elongated webs uniformly to produce neatly rewound rolls having even, trim and square cut ends; and to provide one which is suited for use with any of the foregoing webs.

A further object is to provide a simple, inexpensive and effective form of web slitting mechanism for use with my improved rotary device.

Further objects are: to provide a simple rotary device for the high speed printing, slitting and rewinding of elongated webs; to provide a rotary device of this character which, in one form, is suited for the printing of deformable webs, and, in another form, is suited for the printing of webs of paper; and to provide a device which may with ease be converted from either form to the other.

I have found that I can consistently obtain good printing and rewinding results on deformable web materials simply by placing a supply roll of, and a rewind roll for, such material into interperipheral engagement with an impression cylinder so that the peripheral speeds of all three members of this cluster are always the same despite

2

the constantly changing diameters of the supply and rewind rolls, transferring the supply web from supply roll to the impression cylinder preferably at the area of interperipheral engagement, printing the web as it is carried or conveyed by the impression cylinder and transferring the printed web from the cylinder to said rewind roll preferably at the area of interperipheral engagement.

Polyethylene supply webs are usually wound under a slight degree of tension. When a supply roll of a web of his character is placed in interperipheral engagement with an impression cylinder, the degree of tension that exists in the web on the supply roll will remain unchanged on the impression cylinder because the latter carries the web away from the supply roll at exactly the same rate at which the supply roll feeds the web to the impression cylinder.

The same is true in rewinding when the cylinder and rewind roll are in interperipheral engagement. Here the tension of the web is not affected since the web is rewound by the rewind roll at exactly the same rate as it is fed by the cylinder to that roll.

A rotary press of the foregoing character can be easily, quickly and inexpensively converted into a paper press simply by raising and holding the supply roll out of engagement with the impression cylinder while driving the supply roll at whatever slightly lower speed is required to give the desired degree of tension.

The slitting of the web into two or more narrower webs can be easily and simply accomplished along the path of the web on the cylinder by raising the web slightly out of contact with the cylinder in a manner so that only an extremely short section of the web is out of contact with the cylinder at any one time and slitting the raised web.

The invention is illustrated in the accompanying drawings wherein:

Fig. 1 is a somewhat diagrammatic side elevational view of a rotary printing press constructed in accordance with my invention;

Fig. 2 is a plan view of the Fig. 1 press, the printing rollers shown in Fig. 1, being omitted; and

Figs. 3 and 4 are fragmentary end and face views illustrating the change made in converting the press of Figs. 1 and 2 for use with a paper web.

Polyethylene printing, slitting and rewinding

The embodiment of my invention which is illustrated in Figs. 1 and 2, is intended to perform the operations of printing, slitting and rewinding a "deformable" web such as one composed of polyethylene. However, it will be understood that this embodiment may be employed for performing the rewinding operation either alone or in combination with either or both of the other two operations. This embodiment, more or less specifically stated, comprises: a massive frame; a rotary cluster including a cylinder and first and second web rolls, the periphery of said cylinder providing a snug support for a web extending from one roll to the other; means mounting the members of said cluster on said frame for rotation about parallel axes, said rolls also being mounted for movement bodily toward and away from adjacent peripheral sections of said cylinder; means yieldably holding each roll in interperipheral engagement with its particular section of said cylinder; the periphery of said cylinder providing a substantially continuous web supporting surface extending substantially from one area of interperipheral engagement to the other; drive means for rotating one member of said cluster, said interperipheral engagements being operative to rotate the other members thereof and to maintain the peripheral speeds of the rolls at the same

value as the peripheral speed of the cylinder so that web is unwound from one roll and simultaneously deposited

on said cylinder at the same lineal speed that it is removed from said cylinder and simultaneously deposited on the other roll; means for printing the web on the cylinder; and means for slitting the printed web.

The frame 10 is of the massive character conventionally employed in the printing press art. It is provided with vertical sidewalls 11 and 12 which are of substantial thickness.

The members of the rotary cluster comprise: the impression cylinder 14 and its shaft 15, the web supply roll 16 and its shaft 17; and the web rewind roll 18 and its shaft 19.

All three members of the cluster are mounted on the sidewalls 11 and 12 of the frame 10 for rotation about parallel axes; hence, with their shafts 15, 17 and 19 in parallel relationship. Additionally, the rolls 16 and 18 are also mounted for movement bodily toward and away from different, preferably adjacent, peripheral sections of the cylinder 14. Thus, the supply roll 16 has the ends of its shaft 17 rotationally mounted on the free ends of a pair of arms 21, the opposite ends of which are pivotally mounted on the frame 10 through a shaft 22. Similarly, the rewind roll 18 has the opposite ends of its shaft 19 rotationally mounted upon the free ends of a pair of arms 24, the opposite ends of which are pivotally mounted on the frame through a shaft 25.

The means for yieldably holding each of the rolls 16 and 18 in interperipheral engagement with its particular section of the cylinder 14 may comprise any suitable arrangement of springs or other mechanism for biasing the rolls toward and into yieldable contact with the cylinder. For this purpose, the force of gravity is utilized in the present invention by locating both of the rolls 16 and 18 over the upper half of the cylinder 14 and so arranging their respective pivoting arms 21 and 24 as to cause the rolls to rest gravitationally upon the upper surface of the cylinder, preferably adjacent to but on opposite sides of a vertical plane passing axially through the center of the cylinder 14. The varying pressure of each roll on the cylinder may, if desired, be supplemented or reduced by springs, weights, counterweights or other suitable means.

The periphery of the cylinder 14 preferably provides a substantially continuous web supporting surface from one area of interperipheral engagement to the other. Each area of interperipheral engagement preferably is a web transferring area.

With interperipheral engagement as aforesaid, it is necessary only for the drive means to rotate one member of the cluster, because the interperipheral engagements within the cluster will be operative to rotate the other members thereof and to maintain the peripheral speeds of all members at the same value and thus insure that web will be unwound from one roll and simultaneously transferred to and deposited on the cylinder at the same lineal speed as it is removed from the cylinder and simultaneously transferred to and deposited on the other roll.

While the drive means may be connected to any member of the cluster, it preferably is connected to the impression cylinder 14, first, because it normally will be the largest and heaviest member of the cluster and, second, because its peripheral speed may be more readily controlled since its diameter does not change during a given operation or run. Accordingly, the shaft 15 of the cylinder 14 is provided with a ring gear 26 which is driven by a pinion 27 from any suitable prime mover not shown. The cylinder 14, shaft 15 and gear 26 form a unit which is referred to hereinafter as the "cylinder unit."

The illustrated embodiment includes four printing rollers 30, 31, 32 and 33 rotationally mounted on the frame 10 at appropriately spaced intervals around and in operative printing relationship to the periphery of the impression cylinder. The rollers 30-33 are convention-

ally driven in synchronism with the impression cylinder 14 by means not shown.

It may be noted that, when the printing rollers 30-33 are in operative engagement with a web on the impression cylinder, the type should normally press against the web with a force sufficient to indent the web to a depth equal to and preferably greater than the thickness of the ink film which is printed upon the web. Since there are practical limitations on the printing pressure, the ink film should be relatively thin. The ink should contain a substantial percentage of coloring matter in order that its thin film may "cover" well. Any of the conventional inks for this type of operation may be employed, a fast drying ink of the oil type being preferred.

In lifting and slitting the web, care must be exercised to avoid its deformation. Good results have been obtained with the slitting means illustrated which comprises: a fine wire stretched axially across the periphery of the impression cylinder at a position close to but out of contact with the cylinder and under the web; and means holding one or more knives adjacent the wire with their knife edges pressed resiliently and inwardly against the web, separated slightly from the cylinder by the wire, with sufficient force to slit the web passing therebetween.

The wire 35 should be of small diameter and of substantial tensile strength, such as a piano wire. It is anchored at one end in press frame wall 11 by any suitable means 36. At its other end, it is attached to a tensioning means 37 mounted in the other side wall 12 of the press frame. Both of the wire mounting means 36 and 37 should be radially adjustable in order to facilitate the positioning of the wire at a desired distance from the surface of the cylinder 14 in order to lift the web slightly away from the periphery of the cylinder 14.

Each cutting knife 39 is operatively positioned with its cutting edge pressed yieldably against the web where it is supported from the cylinder 14 by the wire 35. Each knife is mounted on a cross bar 40 which is rigidly secured at its opposite ends to the free ends of a pair of arms 41, the opposite ends of the arms being pivotally mounted on shaft 25 for angular movement independently of the shaft. The force of gravity is relied upon to press the cutting edge of each knife inwardly against the web with the requisite cutting force, but this force may be supplemented or reduced by springs, weights, counterweights and other equivalent means.

In operation, a web from the supply roll is transferred to the impression cylinder at the area of interperipheral engagement, passed around the lower part of the cylinder to the interperipheral web transferring area between the cylinder and the rewind roll on which web is rewound. When the drive means is energized to rotate the impression cylinder at a desired peripheral speed, the cylinder will rotate both the supply and the rewind rolls at the same peripheral speed. This arrangement prevents any relative movement between different portions of the web from the time it leaves the supply roll to the time it reaches the rewind roll; hence stretching, wrinkling, and sagging is prevented, register is insured and smearing is avoided. It is therefore possible to operate it at high speeds up to 1000 feet per minute, more or less, and yet do quality printing work in either black and white or in multi-colors since extremely accurate register is easy to obtain and maintain.

Where a slitter is employed, the web will be rewound in the form of two or more separate rolls but again, due to the precise control of the web, each separate roll will be accurately and evenly rewound into a neat and uniform roll having square cut ends. While the slitting arrangement compels the web to leave the periphery of the impression cylinder for a brief interval during its travel, this does not appear to cause deformation or prevent the securement of extremely good rewinding results.

I have found that the inked impression does not smear or offset when the web is rewound, particularly if the web is allowed to age for a short period, 24 hours being recommended. Apparently, each bit of printed ink lies in the bottom of the depression made by its type and either does not touch the adjacent layer of the rewound web at all or does touch it but with a pressure lighter than that required to effect a transfer of ink. It is easy to understand that smear is avoided because there is no relative movement between the adjacent layers of the web.

Paper printing, slitting and rewinding

The foregoing polyethylene press may be readily adapted for use with elongate "nondeformable" webs, such as paper webs. The conversion of the polyethylene press to a paper press may be accomplished in a simple and effective manner by providing an accessory rotary unit with two circumferential surfaces, one slightly larger than the other, driving the larger circumferential surface at a speed approximating the peripheral speed of the cylinder, and using the smaller slower circumferential surface to drive the supply roll at the same slower peripheral speed.

Accordingly, I provide an accessory roll unit comprising: an accessory roll 45 having a suitable shaft; and a gear 46 mounted on the shaft to rotate therewith. This unit is interposed between the cylinder and the supply roll with its gear 46 meshing with the gear 26 of the cylinder unit and with the circumference of roll 45 engaging the periphery of the supply roll 16. Since the pitch diameter of the large ring gear 26 approximates the diameter of the cylinder 14, their respective peripheral speeds will approximate each other; hence the accessory gear 46 will be driven at a peripheral speed approximating that of the cylinder 14. The peripheral speed, however, of the accessory roll 45 will be slightly lower as its diameter is slightly less than the pitch diameter of the gear 46. The difference between the peripheral speed of the cylinder 14 and the smaller roll 45 is designed to impose the desired degree of tension upon the paper web as it is being fed from the supply roll around the accessory roll 45 to the cylinder 14.

It will be understood that the accessory roll is rotationally mounted on the side walls of the frame in a manner permitting its ready removal. It will therefore be appreciated that this press may be easily and quickly converted from one form to the other. Its operation as a paper press is identical to its operation as a polyethylene press, except for the creation of tension in the paper web.

The term, "deformable web," is used herein to designate polyethylene and like webs which tend to become permanently stretched or deformed if and when the tension of the web, as supplied, is increased. The term, "nondeformable web," is used herein to designate paper and like webs which require additional tension during the rewinding and other operations and which do not tend to become permanently stretched or deformed if and when the tension of the web, as supplied, is increased.

Having described my invention, I claim:

1. A rotary "deformable-web" printing device comprising: a massive frame; a rotary cluster including a massive impression cylinder and web supply and rewind rolls for said deformable-web, all mounted on said frame for rotation about parallel axes, said impression cylinder having a relatively large diameter and weight in comparison with the diameters and weights of the supply and rewind rolls when they are empty of web, said rolls also being mounted for movement bodily toward and away from adjacent peripheral sections of said large impression cylinder; means yieldably holding each roll in nonslipping interperipheral web-transferring engagement with its particular section of said large cylinder; over one half of the periphery of said large cylinder providing a substantially continuous web supporting sur-

face from one area of interperipheral engagement to the other; frame-mounted means for mechanical printing engagement with the web on said web supporting surface; and drive means for continuously rotating said large cylinder, said interperipheral engagements being operative to rotate the other members thereof and to maintain all peripheral speeds of said cluster members at the same value so that web unwound from one roll and simultaneously deposited on said large cylinder at the same lineal speed and under the same tension that it is removed from said large cylinder and simultaneously deposited on the other roll.

2. The device of claim 1 in which each roll is rotationally mounted on the free ends of a pair of spaced arms and the opposite ends of said arms are mounted upon a shaft which is pivotally carried by the frame.

3. The device of claim 1 in which the rolls are located on the upper side of the large cylinder and the force of gravity yieldably urges them toward the large cylinder.

4. The device of claim 1 including: a web slitter positioned close to but out of contact with the periphery of said large cylinder; and means for directing the adjacent section of a web into operative contact with the slitter.

5. The device of claim 4 in which the web directing means comprises a fine wire stretched axially between the large cylinder and the path of the web and adjacent to but out of contact with said large cylinder.

6. The device of claim 5 including: means for adjustably tensioning said wire.

7. The device of claim 1 including means to convert it for use with another or "nondeformable" type of web and cause to tension said other type of web comprising: an accessory roll; means for removably mounting the accessory roll for rotation about an axis parallel to said axes and in a position located between the large cylinder and the supply roll, which must be moved out of engagement with the large cylinder, said accessory roll being mounted with its periphery spaced from the large cylinder but in yieldable interperipheral web-transferring engagement with the supply roll; and means to drive the accessory and supply rolls at a peripheral speed slower than that of the large cylinder.

8. A rotary printing device comprising: the device of claim 1 wherein said supply and rewind rolls are for another type of web material which is to be fed under tension to said large cylinder; and means for holding said supply roll out of interperipheral engagement with said large cylinder and for driving it at a peripheral speed close to but slower than the peripheral speed of the large cylinder so as to tension the web fed from said supply roll to said large cylinder.

9. The device of claim 8 wherein said holding and driving means includes: an accessory roll removably mountable on said frame in a position wherein it is interposed between said supply roll and large cylinder with its periphery spaced from the large cylinder but in interperipheral engagement with said supply roll.

10. The device of claim 9 wherein: the large cylinder drive is operatively connected to the accessory roll through the interperipheral engagement of drive and driven members; the drive member being mounted to rotate with the large cylinder; and the driven member being mounted to rotate the accessory roll and having a diameter larger than the diameter of said accessory roll.

11. A rotary device for tensioning and processing a web comprising: a frame; a rotary cluster including a cylinder, an accessory and web supply and rewind rolls, all mounted on said frame for rotation about parallel axes, said accessory roll being mounted with its periphery adjacent to but spaced from the corresponding periphery of said cylinder; said supply and rewind rolls also being mounted for movement bodily toward and away from the peripheries of said accessory roll and said cylinder respectively; means yieldably holding the supply roll in inter-

peripheral web-transferring engagement with the periphery of said accessory roll; means yieldably holding the rewind roll in interperipheral web-transferring engagement with the periphery of said cylinder; the periphery of said cylinder providing a substantially continuous web supporting surface from adjacent the accessory roll to the rewind roll; drive means for rotating one member of said cluster to drive said cylinder and said rewind roll at the same peripheral speed; and means connecting the cylinder to drive the accessory roll at a lower peripheral speed so that web tends to be unwound from the supply roll at a lineal speed slower than that at which it is removed from said cylinder and simultaneously deposited on the rewind roll.

12. In the art of printing, slitting and rewinding elongate "deformable" webs, such as polyethylene webs, a rotary device for supporting and moving the web along a prescribed path through the device and for rewinding it at the end of said path, comprising: a massive frame, a succession of web-supporting rolls positioned along said path and mounted on said frame, said succession including a supply roll at the beginning of the path, a rewind roll at the end of the path and intermediate-roll-means providing at least one massive intermediate roll along the intermediate portion of said path, said one massive intermediate roll having a relatively large diameter and weight in comparison with the diameters and weights of the supply and rewind rolls when the latter are empty of web, said web extending alternately in one direction around one roll and in the opposite direction, around the next throughout the order of their succession; means mounting every succeeding roll of the succession in non-slipping interperipheral engagement with the immediately preceding roll through the interposed web, the intermediate portion of the web, from the supply to the rewind roll, extending in substantially continuous face-to-face web-supported engagement with the underlying peripheral surface of said intermediate-roll-means including more than one-half of the peripheral surface of said large intermediate roll; and drive means for continuously rotating said large intermediate roll so that all other rolls rotate at speeds determined by their interperipheral engagement, the alternate rolls of the succession rotating

in one direction and the remaining rolls in the reverse direction, and so that, as the web is unwound from the supply roll, conveyed by the intermediate-roll-means and rewound on the rewind roll, it travels at one lineal speed 5 while remaining in substantially continuous face-to-face engagement with web-supporting surfaces traveling at the same lineal speed.

13. The device of claim 12 including means for printing the web as it is conveyed by and supported on said 10 large intermediate roll.

14. The device of claim 12 including means for slitting the web longitudinally as it is conveyed from the supply roll to the rewind roll.

15. The device of claim 14 including means for printing said web as it is conveyed by and supported on said intermediate-roll-means.

16. The device of claim 12 including means to convert it for use with another or "nondeformable" type of web and cause it to tension said other type of web comprising:

20 20 a massive frame, a succession of web-supporting rolls positioned along said path and mounted on said frame, said succession including a supply roll at the beginning of the path, a rewind roll at the end of the path and intermediate-roll-means comprising: an accessory roll; means for removably mounting the accessory roll for rotation about an axis parallel to said axes and in a position located between the large roll and said supply roll, which must be moved out of engagement with the large roll, said accessory roll 25 being mounted with its periphery spaced from the large roll but in yieldable interperipheral web-transferring engagement with the supply roll; and means to drive the accessory and supply rolls at a peripheral speed slower than that of the large roll.
